UNITED STATES PATENT OFFICE.

EMIL FORQUIGNON, OF NEW YORK, N. Y.

DESIGN FOR A NAIL-FILE.

SPECIFICATION forming part of Design No. 31,119, dated July 4, 1899.

Application filed June 7, 1899. Serial No. 719,721. Term of patent 7 years.

To all whom it may concern:

Be it known that I, EMIL FORQUIGNON, a citizen of the United States, residing at New York, in the borough of Manhattan and State of New York, have invented and produced a new and original Design for a Nail-File, of which the following is a specification, reference being had to the accompanying drawings, forming part thereof, in which—

Figure 1 is a side elevation, and Fig. 2 is a section on line 2 2 thereof.

The leading feature of my design is a serrated body provided at one end with a rounded-off portion and at the other end with a shank having incurved side edges and a beak portion extended therefrom and having a straight and a slanting edge.

A indicates the serrated body; B, the rounded-off end portion; C, the shank at the other end, having incurved edges; and D the terminal beak, provided with a straight edge d and a slanting edge d' , which edges d d' run to a point d^2 . 20

What I claim is—

The design for a nail-file, herein shown and 25 described.

In testimony that I claim the foregoing as my invention I have signed my name in presence of two subscribing witnesses.

EMIL FORQUIGNON.

Witnesses:

PAUL GOEPEL,
GEORGE GEIBEL.
